OPERATING MECHANISM

Carl Thumim, Lansdowne, Pa., assignor to General Electric Company, a corporation of New York

Application November 19, 1936, Serial No. 111,709

6 Claims. (Cl. 200—89)

My invention relates to operating mechanisms, more particularly to those of the solenoid actuated type, and has for its principal object the provision of an improved operating mechanism of the aforesaid type which is simple, compact and rugged in construction, efficient, positive and trip-free in operation and which is adapted to apply the operating force directly to a member to be actuated reciprocally movable in a direction generally transverse to the direction of movement of the solenoid armature or plunger.

My invention will be more fully set forth in the following description referring to the accompanying drawings, and the features of novelty which characterize my invention will be pointed out with particularity in the claims annexed to and forming a part of this specification.

Referring to the drawing Fig. 1 is an elevational view partly in section of a solenoid operated mechanism in the operated or "closed" position embodying the present invention; Fig. 2 is a similar view showing the mechanism in an intermediate position during the releasing or tripping operation, and Fig. 3 is a similar view showing the mechanism in the "open" and reset position.

The operating mechanism herein described, while generally applicable to reciprocally movable devices, has particular application to electric circuit breakers wherein a switch member is movable between open and closed circuit positions. In such applications the switch member is generally moved to the closed circuit position against an opening biasing force, such as a compression spring, for example, so that the opening stroke is automatically accomplished simply by release of the switch member. In circuit breaker mechanisms it is also desirable that the device be trip-free in operation, that is, free to trip and release the switch member during any part of the actuating or closing stroke.

Referring more particularly to Fig. 1 there is shown an actuating solenoid generally indicated at 1 including a reciprocally movable plunger 2 which is directly connected through a flexible tension member 3, such as a roller chain linkage for example, to a reciprocally movable switch 4 constituting the means to be actuated. In the present instance the direction of movement of the switch member is substantially at right angles to the direction of movement of the solenoid plunger, so that the chain linkage in applying the actuating force is guided so as to define an angle of approximately 90 degrees.

For the purpose of guiding and restraining the

chain linkage in its operative position, a bell crank 5 pivotally mounted at 6 is provided at one end as at 7 with a roller 8. The bell crank is also provided with a loop-shaped guard member 9 which serves to keep the chain linkage within the groove defined by the roller. The bell crank 5 is also provided at its opposite end as at 10 with a roller 11 coaxing with tripping or restraining means comprising a latch 12 pivotally mounted at 13. The latch is provided with an offset arm 14 for coaxing with the conventional tripping solenoid 15 and is spring biased for resetting at 16 in a counterclockwise direction against the stop member 17.

It will be apparent that actuation of the tripping solenoid to elevate the tripping plunger 15 causes clockwise rotation of the extension 14 and movement of the latch 12 beneath the roller 11. Manual tripping of the latch is suitably provided by means of a lever 18 independently pivotally mounted at 19 and coaxing with a pin 19 carried by the extension arm 14. A manually operable link 20 is connected to the lever 18 for rotating the latch clockwise in the manner above described.

In the position shown by Fig. 1 the switch member 4 is in the operated or closed circuit position and is held in such position against the bias of a compression spring 21. The chain linkage 3 is held under tension by the solenoid plunger 2 while the solenoid is energized. When the solenoid is deenergized a prop member 22 pivotally mounted at 23 is biased as at 24 to block and hold the solenoid plunger in its lower or operated position. The prop 22 is adapted to abut at its lower end a guide pin 25 extending transversely of the plunger within a recess in the central part thereof and operable within lateral guide plates 25'.

The bell crank 5, the pivot 6 of which is offset with respect to the bisector of the angle defined by the chain linkage so that the chain tension tends to rotate the bell crank clockwise, is restrained with respect to clockwise rotation by the latch 12 as previously described. In this position the solenoid can be deenergized and the switch member 4 held indefinitely in the closed circuit position.

The releasing or circuit opening operation is initiated by releasing or tripping of the bell crank by the latch 12, either by the tripping solenoid or manual operation, so that the spring 21 tensioning the chain linkage 3 causes clockwise rotation of the bell crank to the position shown by Fig. 2. A comparatively sensitive tripping device can be used if desired since the required

tripping force is directly related to the crank lever arm indicated at "a" through which the resultant reacting force at the chain linkage tends to produce clockwise rotation of the crank. 5 Where the lever arm "a" is quite small, the latch releasing force required is obviously small.

During the releasing movement of the bell crank a portion thereof at 5' serves as a cam member for engaging an extension 26 secured to 10 the prop 22. After predetermined rotation of the bell crank the member 26 is cammed so as to move the prop 22 away from the solenoid pin 25. Accordingly the plunger 2, which is normally biased, in addition to the bias of spring 21, by a 15 spring 27 towards its upper or reset position, is now free to assume such position.

It will be apparent that release of the bell crank 5 causes sufficient slack in the chain linkage to permit immediate opening movement of the 20 switch member. In addition, the release of the solenoid plunger in response to release of the bell crank causes immediate resetting of the solenoid so that another reclosing operation is dependent only upon resetting of the bell crank and latch. 25 To this end the bell crank is provided with a resetting spring 28 which is tensioned during the opening operation and which functions immediately to reset the bell crank as illustrated by Figs. 2 and 3 as soon as there is sufficient slack 30 in the chain linkage.

In resetting the roller 11, the bell crank rides over the edge of the latch 12, thereby effecting resetting of the tripping means. The mechanism illustrated by Fig. 3 is therefore in the completely reset position and can be closed by energization of the solenoid causing downward movement of the plunger 2 to the position illustrated by Fig. 1.

During the closing operation the bell crank 5 40 is held in the position shown and the chain linkage is guided by the roller 8 so that the actuating force is applied through an angle of 90 degrees without appreciable friction losses. When the plunger 2 reaches the lower position shown by 45 Fig. 1 the prop 22 is snapped by its spring 24 over the pin 25 so as to block return movement of the plunger except in accordance with a duly initiated opening operation.

It will be noted that the mechanism is trip- 40 free in all positions thereof during the actuating or closing stroke. That is, actuation of the tripping mechanism is effective at any time to produce sufficient slack in the chain linkage to permit reverse or opening movement of the switch member.

It should be understood that my invention is not limited to specific details of construction and arrangement thereof herein illustrated, and that changes and modifications may occur to one 60 skilled in the art without departing from the spirit of my invention.

What I claim as new and desire to secure by Letters Patent of the United States is:

1. Operating mechanism comprising actuating 65 means and means to be actuated, a continuous flexible tension member interconnecting the aforesaid means for changing the direction of application of the actuating force, said flexible member being under tension when said actuating 70 force is applied, means for guiding and restraining said flexible member for effecting the aforesaid change in direction of actuating force, said guiding and restraining means including a crank having a comparatively small effective lever arm 75 in the operative position, and tripping means

causing release of said guiding means so that the resulting slack in said flexible member permits reverse movement of said means to be actuated.

2. Operating mechanism comprising actuating 5 means and means to be actuated, a flexible tension member interconnecting the aforesaid means and adapted to be tensioned by said actuating means for changing the direction of application of the actuating force, means including a crank coacting at one end with said tension member for guiding and restraining the same so that said change in direction is of the order of 90 degrees, and tripping means for releasing said crank so that the resulting slack in said tension member permits reverse movement of said means to be actuated. 15

3. Operating mechanism comprising an actuating solenoid having a reciprocally operable plunger, a member to be actuated reciprocally movable in a direction generally transverse to the 20 direction of movement of said plunger, a flexible tension member interconnecting said plunger and said member, a pivoted element including a roller mounted at one end thereof for coacting with said tension member for guiding and restraining the same along a path of changing direction, actuation of said solenoid effecting a pull on said tension member to move said reciprocally operable member in one direction, and tripping means for releasing said pivoted member so that the resulting slack in said tension member permits reverse movement of said reciprocally operable member. 30

4. Operating mechanism comprising an actuating solenoid having a reciprocally operable plunger, a member reciprocally movable in a direction generally transverse to the direction of movement of said plunger, a chain linkage interconnecting said member and said plunger, a bell crank having a roller at one end for guiding and restraining said chain linkage in tension, the 40 pivot of said bell crank being disposed within the angle through which said chain linkage is tensioned so that the reacting force on said bell crank tends to rotate the same from its restraining position, and latching means coacting with the other end of said bell crank for releasing the same so that said chain linkage is slackened and ineffective to hold said reciprocally operable member in its operated position. 45

5. Operating mechanism of the trip-free type 50 for electric circuit breakers comprising a solenoid having a reciprocally operable plunger, a switch member reciprocally operable in a direction generally transverse to the direction of movement of said plunger, a chain linkage interconnecting said plunger and said switch member, a bell crank having a roller at one end for guiding and restraining said chain linkage along a path defining an angle of approximately 90 degrees, the tension applied by said plunger to said chain linkage in operating said switch member to the closed circuit position tending to rotate said bell crank to a non-restraining position, a resetting spring biasing said bell crank toward said position, a prop member normally restraining said plunger in its operated position, said bell crank being adapted to cause release of said prop in accordance with releasing movement of said bell crank and tripping means coacting with said bell crank for restraining the same and said chain linkage in an operative position, actuation of said tripping means causing rotation of said bell crank so that the resulting slack in said chain linkage permits circuit opening movement of said switch member. 60

6. Operating mechanism for electric switches comprising an actuating solenoid having a reciprocally operable plunger, a switch member reciprocally movable in a direction approximately 5 at right angles to the direction of movement of said plunger, a chain linkage interconnecting said plunger and switch member, a bell crank having a guide roller for said chain for restraining said chain along a path generally coincident with the 10 angle between said directions of movement, the pivot of said bell crank being within said angle

and offset with respect to the bisector of said angle so that tension applied to said chain by said plunger tends to rotate said bell crank from its restraining position, and latching means coacting with said bell crank for holding the same in said restraining position, actuation of said latching means and the resulting slack in said chain linkage permitting reverse movement of said switch member. 5

CARL THUMIM. 10
